UNITED STATES PATENT OFFICE.

CLARENCE B. HAYES, OF JACKSON, MICHIGAN.

MACHINE FOR REMOVING CLEATS FROM FELLIES.

1,091,840.

Specification of Letters Patent. Patented Mar. 31, 1914.

Application filed September 18, 1911. Serial No. 649,969.

To all whom it may concern:

Be it known that I, CLARENCE B. HAYES, a citizen of the United States, residing at Jackson, Michigan, have invented certain new and useful Improvements in Machines for Removing Cleats from Fellies, of which the following is a specification.

This invention relates to improvements in machines for removing cleats from fellies.

10 The machine is a modification in some particulars, and in other particulars an improvement, on the machine appearing in my Patent No. 1,010,424, dated December 5, 1911, for a machine for removing cleats from fellies.

15 The objects of the present invention are to provide a simple and strong machine that will effectively remove the cleats from fellies without waste.

20 Objects relating to details of the mechanism and economies of construction will definitely appear from the detailed description to follow.

I accomplish the objects of my invention 25 by the devices and means described in the following specification.

The invention is clearly defined and pointed out in the claims.

25 A machine constituting an effective and preferred embodiment of my invention is clearly illustrated in the accompanying drawing, forming a part of this specification, in which:

Figure I is a side elevation view of my 35 improved machine without the fellies in position. Fig. II is a plan view of the structure appearing in Fig. I, with the fellies and cleats thereon in position. Fig. III is a vertical longitudinal sectional elevation through 40 the machine, taken on a line corresponding to line 3—3 of Figs. II and IV, showing the fellies and the cleats thereon in position. Fig. IV is a detail sectional view taken on a line corresponding to the irregular line 4—4

45 of Figs. I and III, showing details of the clutch mechanism and of the operating means. Fig. V is an enlarged detail front elevation view of the adjustable abutments for removing the fellies.

50 In the drawings, the sectional views are taken looking in the direction of the little arrows at the ends of the section lines, and similar numerals of reference refer to similar parts throughout the several views.

55 In general, my improved cleat removing machine consists of a frame, carrying a pair of adjustable abutments, and a reciprocating

clamp head, in which the fellies are placed with the cleats so disposed that on the reciprocation of the head the fellies will be 60 separated from the cleats and the cleats thereby removed.

Referring to the numbered parts of the drawing, the main frame 1 is carried on suitable legs 2—2. The reciprocating head 3 is 65 on ways 5. On this head a downwardly-projecting engaging portion 4 extends between the ways to give added security thereto. A fixed clamp jaw 6 is on this stationary head, and a movable jaw 7 is adapted to be 70 clamped against the fellies 8 by the screw 10, extending in a threaded bore 11 in the movable jaw of the clamp. The said screw is journaled at 12 in an upwardly projecting portion of the reciprocating head, and 75 is controlled by the crank 13 by which the same can be readily adjusted to clamp the fellies placed in the machine between the jaws.

The reciprocating head is adjustable by 80 revolvable shaft 14, which is screw threaded at 15 extending through a threaded bore 16 in a downwardly-projecting boss underneath the reciprocating head. The shaft is journaled in a downwardly-projecting portion 17 of the frame, and is controlled by a crank 18 by which the reciprocating head is 85 adjusted on the ways. The head is reciprocated from the eccentric 19 which is on transverse shaft 20. A coupling rod 21 extends from the said eccentric to a pivot 22 in a loose collar 23, in which the outer end of the shaft 14 is journaled. A stop collar 24 on shaft 14 affords the resistance to collar 23 so that the eccentric may act by its coupling. 90 The shaft 20 is journaled in hangers 25—25 beneath the frame. The shaft 20 is driven by the gear wheel 26 which meshes with suitable driving gear hereafter to be described.

The gear wheel is provided with a clutch 100 member 27 which coacts with a clutch member 28 on the shaft 20, which parts are under control of the clutch lever 29 which is fulcrumed at 29' in a block on the floor beneath. A cam arm 30 is on this clutch lever, and coöperates with a stop pin 31 on the clutch member 27 which is driven by the wheel 26. It will therefore be seen that whenever the clutch is thrown into engagement, as soon as it turns over the pin 31 110 strikes the cam member 28 and throws the clutch out of engagement, so that there is but a single rotation whenever the machine is brought into operation. Whenever the

machine is thus brought into operation, the clamp head is reciprocated a single stroke, which is sufficient for the removing of the cleats from the fellies.

5 The gear 26 is driven by the pinion 35 which is on the countershaft 34, which is driven by pulley 33.

10 Adjustable abutments 36 are secured by guide brackets 37-38 to cross arms 39 of the frame 1. These abutments are adjustable back and forth by the right and left hand screw 40, which is supported in journal bearings 41-42 at each end of the said cross arms.

15 It will thus be seen that in operation, when the fellies with the cleats on are placed in the machine, they are clamped between the jaws 6 and 7. When the clutch lever 29 is operated, the eccentric reciprocates the 20 clamp head a single stroke, and owing to the fact that the cleats are engaged by the abutments 36-36, they are stripped off and drop down at the end of the machine. It will thus be seen that a very simple and 25 effective machine for this purpose is provided, which is completely and effectively adjustable. Of course, where a single size of fellies is being manufactured and handled, no adjustment of the machine is necessary, it being made the right size in the first 30 place. Also, it will be observed that in the particular form of machine I have here produced, it is not necessary to clamp the felly section with a high pressure, because the action 35 of the machine is such that the felly sections would not be displaced anyhow to any great extent, and only slight resistance is necessary in the clamp.

I desire to claim the invention broadly 40 and also specifically, as appears in the appended claims.

Having thus described my invention, what I claim as new and desire to secure by Letters Patent is:

45 1. In a machine for removing cleats from fellies, the combination of a suitable supporting frame; a reciprocating head in suitable ways on said frame; clamping jaws on said reciprocating head conformed to the 50 fellies; a screw for closing the said jaws onto the fellies; a shaft with an adjusting screw engaging a suitable threaded bore in the said reciprocating head and slidably supported in a suitable bearing in the said frame; a suitable transverse shaft with eccentric disposed beneath said frame; a pitman connected to said eccentric and a loose collar embracing the said shaft to which said pitman is connected; a stop collar on said shaft for limiting the movement of said loose collar; suitable means for driving the said shaft; a clutch for throwing the said eccentric into gear; means for tripping the said clutch to release at each revolution; and suitable 55 adjustable abutments supported on the said frame and disposed to coöperate with the said reciprocating head and its clamping jaws, all coacting substantially as described and for the purpose specified.

60 2. In a machine for removing cleats from fellies, the combination of a suitable supporting frame; a reciprocating head in suitable ways on said frame; clamping jaws on said reciprocating head conformed to the fellies; a suitable transverse shaft with eccentric disposed beneath said frame; a pitman connected to said eccentric to reciprocate said head; suitable means for driving 65

the said frame and disposed to coöperate with the said reciprocating head and its clamping jaws; and a right and left hand screw for adjusting the said abutments, coacting substantially as described and for the purpose specified.

70 2. In a machine for removing cleats from fellies, the combination of a suitable supporting frame; a reciprocating head in suitable ways on said frame; clamping jaws on said reciprocating head conformed to the fellies; a screw for closing the said jaws onto the fellies; a shaft with an adjusting screw engaging a suitable threaded bore in the said reciprocating head and slidably supported in a suitable bearing in the said frame; a suitable transverse shaft with eccentric disposed beneath said frame; a pitman connected to said eccentric and a loose collar embracing the said shaft to which said pitman is connected; a stop collar on said shaft for limiting the movement of said loose collar; suitable means for driving the said shaft; a clutch for throwing the said eccentric into gear; means for tripping the said clutch to release at each revolution; and suitable adjustable abutments supported on the said frame and disposed to coöperate with the said reciprocating head and its clamping jaws, all coacting substantially as described and for the purpose specified.

75 3. In a machine for removing cleats from fellies, the combination of a suitable supporting frame; a reciprocating head in suitable ways on said frame; clamping jaws on said reciprocating head conformed to the fellies; a shaft with an adjusting screw engaging a suitable threaded bore in the said reciprocating head and slidably supported in a suitable bearing in the said frame; a suitable transverse shaft with eccentric disposed beneath said frame; a pitman connected to said eccentric and a loose collar embracing the said shaft to which said pitman is connected; a stop collar on said shaft for limiting the movement of said loose collar; suitable means for driving the said shaft; a clutch for throwing the said eccentric into gear; means for tripping the said clutch to release at each revolution; and suitable adjustable abutments supported on the said frame and disposed to coöperate with the said reciprocating head and its clamping jaws, all coacting substantially as described and for the purpose specified.

80 4. In a machine for removing cleats from fellies, the combination of a suitable supporting frame; a reciprocating head in suitable ways on said frame; clamping jaws on said reciprocating head conformed to the fellies; a suitable transverse shaft with eccentric disposed beneath said frame; a pitman connected to said eccentric to reciprocate said head; suitable means for driving

- the said shaft; a clutch for throwing the said eccentric into gear; means for tripping the said clutch to release at each revolution; and suitable abutments supported 5 on the said frame and disposed to coöperate with the said reciprocating head and its clamping jaws, all coacting substantially as described and for the purpose specified.
5. In a machine for removing cleats from 10 fellies, the combination of a suitable supporting frame; a reciprocating head in suitable ways on said frame; clamping jaws on said reciprocating head conformed to the fellies; a screw for closing the said jaws 15 onto the fellies; a shaft with an adjusting screw engaging a suitable threaded bore in the said reciprocating head and slidably supported in a suitable bearing in the said frame; a suitable transverse shaft with eccentric disposed beneath the said frame; a 20 pitman connected to said eccentric and a loose collar embracing the said shaft to which said pitman is connected; a stop collar on said shaft for limiting the movement 25 of said loose collar; suitable means for driving the said shaft; a clutch for throwing the said eccentric into gear; suitable adjustable abutments supported on the said frame and disposed to coöperate with the said reciprocating head and its clamping jaws; and 30 right and left hand screw for adjusting the said abutments, all coacting substantially as described and for the purpose specified.
6. In a machine for removing cleats from 35 fellies, the combination of a suitable supporting frame; a reciprocating head in suitable ways on said frame; clamping jaws on said reciprocating head conformed to the fellies; a screw for closing the said jaws 40 onto the fellies; a shaft with an adjusting screw engaging a suitable threaded bore in the said reciprocating head and slidably supported in a suitable bearing in the said frame; a suitable transverse shaft with eccentric disposed beneath said frame; a pitman connected to said eccentric and a loose collar embracing the said shaft to which said pitman is connected; a stop collar on said shaft for limiting the movement 45 of said loose collar; suitable means for driving the said shaft; a clutch for throwing the said eccentric into gear; and suitable adjustable abutments supported on the said frame and disposed to coöperate with the said reciprocating head and its clamping jaws, all coacting substantially as described and for the purpose specified.
7. In a machine for removing cleats from 50 fellies, the combination of a suitable supporting frame; a reciprocating head in suitable ways on said frame; clamping jaws on said reciprocating head conformed to the fellies; adjustable means to reciprocate said head; suitable abutments supported on the said frame and adapted to engage the cleats, all coacting substantially as described and for the purpose specified.
8. In a machine for removing cleats from 55 fellies, the combination of a suitable supporting frame; a reciprocating head in suitable ways on said frame; clamping jaws on said reciprocating head conformed to the fellies; a clutch for throwing the said eccentric into gear; and suitable adjustable abutments supported on the said frame and disposed to coöperate with the said reciprocating head and its clamping jaws, all coacting substantially as described and for the purpose specified.
9. In a machine for removing cleats from 60 fellies, the combination of a suitable supporting frame; a reciprocating head in suitable ways on said frame; clamping jaws on said reciprocating head conformed to the fellies; a shaft with an adjusting screw en-
- gaging a suitable threaded bore in the said reciprocating head and slidably supported 65 in a suitable bearing in the said frame; a suitable transverse shaft with eccentric disposed beneath said frame; a pitman connected to said eccentric and a loose collar embracing the said shaft to which said pitman is connected; a stop collar on said shaft for limiting the movement of said loose collar; suitable means for driving the said shaft; a clutch for throwing the said eccentric into gear; and suitable adjustable abutments supported on the said frame and disposed to coöperate with the said reciprocating head and its clamping jaws, all coacting substantially as described and for the purpose specified.
10. In a machine for removing cleats from 65 fellies, the combination of a suitable supporting frame; a reciprocating head in suitable ways on said frame; clamping jaws on said reciprocating head conformed to the 70 fellies; a suitable transverse shaft with eccentric disposed beneath said frame; a pitman connected to said eccentric to reciprocate said head; suitable means for driving the said shaft; a clutch for throwing the said eccentric into gear; and suitable abutments supported on the said frame and disposed to coöperate with the said reciprocating head and its clamping jaws, all coacting substantially as described and for the purpose specified.
11. In a machine for removing cleats from 75 fellies, the combination of a suitable supporting frame; a reciprocating head in suitable ways on said frame; clamping jaws on said reciprocating head conformed to the 80 fellies; a suitable transverse shaft with eccentric disposed beneath said frame; a pitman connected to said eccentric and a loose collar embracing the said shaft to which said pitman is connected; a stop collar on said shaft for limiting the movement of said loose collar; suitable means for driving the said shaft; a clutch for throwing the said eccentric into gear; and suitable adjustable abutments supported on the said frame and disposed to coöperate with the said reciprocating head and its clamping jaws, all coacting substantially as described and for the purpose specified.
12. In a machine for removing cleats from 85 fellies, the combination of a suitable supporting frame; a reciprocating head in suitable ways on said frame; clamping jaws on said reciprocating head conformed to the 90 fellies; a suitable transverse shaft with eccentric disposed beneath said frame; a pitman connected to said eccentric to reciprocate said head; suitable means for driving the said shaft; a clutch for throwing the said eccentric into gear; and suitable abutments supported on the said frame and disposed to coöperate with the said reciprocating head and its clamping jaws, all coacting substantially as described and for the purpose specified.
13. In a machine for removing cleats from 95 fellies, the combination of a suitable supporting frame; a reciprocating head in suitable ways on said frame; clamping jaws on said reciprocating head conformed to the 100 fellies; a suitable transverse shaft with eccentric disposed beneath said frame; a pitman connected to said eccentric and a loose collar embracing the said shaft to which said pitman is connected; a stop collar on said shaft for limiting the movement of said loose collar; suitable means for driving the said shaft; a clutch for throwing the said eccentric into gear; and suitable adjustable abutments supported on the said frame and disposed to coöperate with the said reciprocating head and its clamping jaws, all coacting substantially as described and for the purpose specified.
14. In a machine for removing cleats from 105 fellies, the combination of a suitable supporting frame; a reciprocating head in suitable ways on said frame; clamping jaws on said reciprocating head conformed to the 110 fellies; a shaft with an adjusting screw for adjusting said head; and suitable abutments supported on the said frame and adapted to engage the cleats, all coacting substantially as described and for the purpose specified.
15. In a machine for removing cleats from 115 fellies, the combination of a suitable supporting frame; a reciprocating head in suitable ways on said frame; clamping jaws on said reciprocating head conformed to the 120 fellies; adjustable means to reciprocate said head; suitable abutments supported on the said frame and adapted to engage the cleats; and means for adjusting said abutments to and from each other, all coacting substantially as described and for the purpose specified.

In witness whereof, I have hereunto set my hand and seal in the presence of two witnesses.

CLARENCE B. HAYES. [L. S.]
